CLAIM

The ornamental design for a digital audio control equipment, as shown and described.

DESCRIPTION

FIG. 1 is a top-right-front perspective view of a digital audio control equipment, showing the new design;

FIG. 2 is a bottom-left-rear perspective view thereof, and does not show any portion of the claimed design;

FIG. 3 is top view thereof;

FIG. 4 is bottom view thereof, and does not show any portion of the claimed design;

FIG. 5 is an enlarged view thereof, taken from FIG. 1, and shows details of the design not amenable for depiction in the view of FIG. 1; and,

FIG. 6 is an enlarged view thereof, taken from FIG. 3, and shows details of the design not amenable for depiction in the view of FIG. 3.

The evenly spaced dash-dash-dash broken lines depict portions of the digital audio control equipment that form no part of the claimed design.

The dot-dash broken lines forming two circles of FIGS. 1, 3, 5, and 6 represent boundaries between the claimed area and unclaimed areas only and form no part of the claimed design.

The dot-dot-dash broken lines of FIGS. 1, 3, 5, and 6 are included to show boundaries of enlarged views only and form no part of the claimed design.

The concentric arc-shaped lines represented in each area between adjacent arcuate buttons shown in FIGS. 1, 3, 5, and 6 are printed patterns on the surface of a housing.
